UNITED STATES PATENT OFFICE.

JAMES G. NOLEN, OF NEW YORK, N. Y.

TONE MODIFIER.

Application filed December 11, 1924. Serial No. 755,213.

The present invention relates to radio or phonograph horns and particularly to means for modifying and modulating the sound emitted thereby, and one object of the invention is to provide in a radio or phonograph horn a resonator which receives the sound from the radio apparatus or phonograph and a tone modifier and modulator cooperating with the resonator.

Another object of the invention is to provide in a radio or phonograph horn a resonator which receives the sound from the radio apparatus or phonograph, and a tone modifier and modulator cooperating with the resonator and provided with means for regulating the modifier and modulator.

These objects and such other objects as may later appear herein are attained by the invention two of the possible embodiments of which are described by way of example in the subjoined specification and shown in the drawing accompanying the specification in which Fig. 1, is a side view of one form of the resonator and tone modifier applied to a radio or phonograph horn, the resonator and a portion of the horn being in section.

Fig. 2, is a front view of the form of the invention shown in Fig. 1, the casing of the horn being partly broken away to show the tone modifier and modulator.

Fig. 3, is a side view of the resonator and another form of tone modifier and modulator applied to a radio or phonograph horn, the resonator and a portion of the horn and the tone modifier and modulator being in section.

Fig. 4 is a view on the line 4—4 of Fig. 3, looking in the direction of the arrows.

Fig. 5, is a sectional view of the resonator and showing one of the diaphragms thereof and its retaining ring removed from and in adjacency to the resonator.

Fig. 6, is a side view of the resonator applied to a radio or phonograph horn and without the tone modifier and modulator, and showing the manner of securing the resonator in the horn,

Fig. 7, is a sectional view of the resonator shown in Fig. 6 and showing a convenient way of securing the diaphragm to the body of the resonator and providing means for securing the resonator in the horn as seen in Fig. 6, and

Fig. 8 is an end view of the resonator.

Similar reference characters denote similar parts throughout the several views.

Referring to Fig. 1, the invention comprises a horn having the mouth 10, the neck 11, the extended circular intermediate portion 12 flat on opposite sides, and the resonator 13 received in the neck 11 of the horn 11 which in turn is received in the extension 14 of the sound box 15.

The resonator 13 is of suitable light weight metal, such as aluminum, cylindrical in form and has the venturi or substantially hour-glass shaped opening 16 therethrough for passage of sound, this venturi or opening being provided with the steps or series of transverse corrugations 17 and 18 extending inwardly from each end of the venturi or opening and meeting at about the middle transverse line thereof.

The diaphragm 19 is arranged at the sound receiving end of the venturi 16 and is provided with the centrally located aperture 20, and the diaphragm 21 is arranged at the opposite end of the venturi and is provided with the centrally located aperture 22, the aperture 20 being smaller than the aperture 22. The diaphragms 19 and 21 are of different resiliency, the diaphragm 19 in the present instance being of silk and the diaphragm 21 being of rubber. The diaphragms 19 and 21 are secured in the venturi 16 by turning up the ends of the diaphragms and pressing the upturned ends against the adjacent inner walls of the venturi by means of retaining rings 23 and 24, the apertures 20 and 22 being in axial alignment.

The resonator 13 is inserted in the neck 11 of the horn and is frictionally held therein, the diaphragm 19 being outward or towards the interior of the sound box 15 and the diaphragm 21 being inward or towards the interior of the extension 12 of the horn, it being understood that the neck 11 of the horn is then located and frictionally held in the extension 14 of the sound box.

The extension 12 of the horn has in its interior the circular partition 25 which provides diverging passages X and Y for sound from the diaphragm 21 to the mouth 10 of the horn. The passage Y has the diaphragm 26 of rubber arranged across it extending in the diametric line of the extension 12 from near the adjacent end of the neck 11 to the partition 25, the diaphragm 26 being provided with the central aperture 27 which is smaller than either of

2 the apertures 20 or 22 of the diaphragms 19 and 21.

The partition 25 is provided with the opening 28 and has located centrally of the partition the spindle or shaft 29 seated at each of its ends for turning movement in opposite walls of the extension 12, the spindle 29 being provided on the exterior of the horn with the finger 30 for turning the 10 spindle.

The butterfly 31 is secured at one of its ends to the spindle 29 for turning therewith and passing through the opening 28 extends across the passage X for preventing passage of sound therethrough being limited in swinging movement in one direction by the stop strip 32 and in the opposite direction by covering contact with the diaphragm 26.

20 The butterfly 31 carries the cover plate 33 for preventing passage of sound through the opening 28 to the interior space enclosed by the partition 25.

The spindle 29 is so frictionally held in its bearings that when turned by the finger piece 30 the spindle and butterfly 31 will remain in the position to which they are turned thus providing when brought into contact with the stop strip 32 for the passing from the resonator 13 into the passage Y and thence to the mouth 10 of the horn by way of the diaphragm 26 of sound emanating from the resonator and modulated by the diaphragm 26, and providing 30 when the butterfly is brought into covering contact with the diaphragm 26 for the passing from the resonator 13 into the passage X and thence to the mouth 10 of the horn of sound emanating directly from the resonator and free from action of the diaphragm 26, modification of these effects being obtained by setting the butterfly 31 at intermediate positions between the strip 32 and diaphragm 26.

45 Referring to Figs. 3 and 4, the resonator 34 is similar to the resonator 13 and is received in the cylindrical casing 35, this casing, substantially at the line of the inner diaphragm of the resonator when the 50 resonator is located in the casing, being extended to provide the offset 36 for supporting for pivotal movement the shank 37 of the diaphragm carrier 38 in which is secured by means of the retaining ring 39 55 the diaphragm 40 of rubber having the aperture 41, which aperture is smaller than either of the apertures of the diaphragms of the resonator 34. The shank 37 has cooperating therewith for pivotally moving 60 the diaphragm carrier 38 the finger piece 42 whereby the carrier 38 and diaphragm 40 may be moved in the casing 35 from a transverse position therein to an inclined position shown by the dot and dash lines, the 65 intention being that when in transverse

position the diaphragm 40 cooperating with the resonator 34 shall provide in the upper portion of the casing 35 sound emanating from the resonator 34 and modulated by the diaphragm 40, and when the carrier 38 and diaphragm 40 are moved to inclined position sound is provided in the upper portion of the casing as emanating directly from the resonator 34 and substantially free from action of the diaphragm 40, the effect 70 being substantially the same as the movement of the butterfly 31 relative to the diaphragm 26 before described, the carrier 38 being settable at intermediate position for modifying the effect, it being understood 75 that the lower end of the horn 42 is received in the upper end of the casing 35 and frictionally held therein and that the lower end of this casing is inserted in a sound duct, not shown, or in an extension, not 80 shown, of a sound box also not shown and frictionally held therein.

Referring to Figs. 6 and 7, the resonator 43 is similar to the resonators 13 and 34 except that the diaphragm 44 is glued, 90 cemented or otherwise suitably secured to the outer side of the body portion of the resonator, and the diaphragm 45 is secured on the outer side of the body of the resonator by the retaining ring 46 exteriorly engaging said body, a resonator thus being 95 provided which is readily insertable in a horn 47 which is not provided with tone modifying and modulating means.

Having thus described my invention it 100 should be understood that there may be modifications thereof and variations therein without departing from the spirit of the invention, or exceeding the scope of the appended claims.

105 What I claim and desire to protect by Letters Patent is:

1. In combination with a sound duct, a resonator having a venturi like opening passing therethrough, and means for modifying and modulating sound cooperating 110 with the resonator.

2. In combination with a sound duct, a resonator comprising opposed diaphragms and means for passage of sound between the 115 diaphragms, and means for modifying and modulating sound cooperating with the resonator.

3. In combination with a sound duct, a resonator comprising opposed diaphragms and a venturi for passage of sound between the diaphragms, and means for modifying 120 and modulating sound cooperating with the resonator.

4. In combination with a sound duct, a resonator comprising opposed diaphragms and a venturi having stepped walls for passage of sound between the diaphragms, and means for modifying and modulating 125 sound cooperating with the resonator.

5. In combination with a sound duct, a resonator comprising opposed diaphragms and a venturi having transverse corrugations on its walls for passage of sound between the diaphragms, and means for modifying and modulating sound cooperating with the resonator.
6. In combination with a sound duct a resonator comprising opposed diaphragms of different resiliency and means for passage of sound between the diaphragms, and means for modifying and modulating sound cooperating with the resonator.
7. In combination with a sound duct, a resonator comprising opposed diaphragms of different resiliency and a venturi for passage of sound between the diaphragms, and means for modifying and modulating sound cooperating with the resonator.
8. In combination with a sound duct, a resonator comprising opposed diaphragms, one of silk and the other of rubber and a venturi for passage of sound between the diaphragms, and means for modifying and modulating sound cooperating with the resonator.
9. In combination with a sound duct, a resonator comprising opposed diaphragms each having an aperture therethrough and said apertures differing in size and means for passage of sound between the diaphragms, and means for modifying and modulating sound cooperating with the resonator.
10. In combination with a sound duct, a resonator comprising opposed diaphragms each having an aperture therethrough and said apertures differing in size and a venturi for passage of sound between the diaphragms, and means for modifying and modulating sound cooperating with the resonator.
11. In combination with a sound duct, a resonator, a diaphragm for receiving sound from the resonator for modulating the sound, and means for modifying the sound from the resonator by providing passage for the sound from the resonator free from action of said diaphragm.
12. In combination with a sound duct, a resonator, a diaphragm for receiving sound from the resonator for modulating the sound, and means for modifying the sound from the resonator by preventing vibratory contact of the sound with said diaphragm and diverting from said diaphragm the sound from the resonator during passage of the sound.
13. In combination with a sound duct, a resonator, a diaphragm for receiving sound from the resonator for modulating the sound, and means for modifying the sound from the resonator by partially diverting from the diaphragm the sound from the resonator during passage of the sound.
14. In combination with a sound duct, a resonator, a diaphragm for receiving sound from the resonator for modulating the sound, and settable movable means for modifying the sound from the resonator by partially diverting from the diaphragm the sound from the resonator during passage of the sound.
15. In combination with a horn having a neck, a resonator having a venturi like opening passing therethrough arranged in the neck of the horn.
16. In combination with a horn having a neck, a resonator arranged in the neck of the horn and comprising opposed diaphragms and means for passage of sound between the diaphragms.
17. In combination with a horn having a neck, a resonator arranged in the neck of the horn and comprising opposed diaphragms and a venturi for passage of sound between the diaphragms.
18. In combination with a horn having a mouth and a neck, a resonator having a venturi like opening passing therethrough arranged in the neck of the horn, and means for modifying and modulating sound cooperating with the resonator and arranged in the horn between the resonator and mouth.
19. In combination with a horn having a mouth and a neck, a resonator arranged in the neck of the horn, and means for modifying and modulating sound arranged in the horn between the resonator and mouth, said means comprising a diaphragm for receiving sound from the resonator for modulating the sound and means for modifying the sound from the resonator by diverting from the diaphragm said sound during passage of the sound from the resonator to the mouth of the horn.
20. In combination with a horn having a mouth and a neck, a resonator arranged in the neck of the horn, and means for modifying and modulating sound arranged in the horn between the resonator and mouth, said means comprising a diaphragm for receiving sound from the resonator for modulating the sound and regulatable means for modifying the sound from the resonator by partially diverting said sound from the diaphragm during passage of the sound from the resonator to the mouth of the horn.
21. In combination with a horn having a mouth and a neck, a resonator arranged in the neck of the horn, and means for modifying and modulating sound arranged in the horn between the resonator and mouth, said resonator comprising opposed diaphragms and a venturi for passage of sound between the diaphragms, said means comprising a diaphragm for receiving sound from the resonator for modulating the sound and means for modifying the sound from the

- resonator by diverting said sound from the last mentioned diaphragm during passage of the sound from the resonator to the mouth of the horn.
22. In combination with a horn having a mouth and a neck, a resonator arranged in the neck of the horn, and means for modifying and modulating sound arranged in the horn between the resonator and mouth, said resonator comprising opposed diaphragms and a venturi for passage of sound between the diaphragms, said means comprising a diaphragm for receiving sound from the resonator for modulating the sound and regulatable means for modifying the sound from the resonator by partially diverting said sound from the last mentioned diaphragm during passage of the sound from the resonator to the mouth of the horn.
23. In combination, a resonator comprising opposed diaphragms and means for providing passage for sound between the diaphragms, and a diaphragm cooperating with the resonator for modulating the sound emanating therefrom.
24. In combination, a resonator comprising opposed diaphragms of different resiliency and a venturi for providing passage for sound between the diaphragms, and a diaphragm cooperating with the resonator for modulating the sound emanating therefrom.
25. In combination, a resonator comprising opposed diaphragms of different resiliency each having an aperture therethrough and the apertures differing in size and a venturi for providing passage of sound between the diaphragms, and a diaphragm cooperating with the resonator for modulating the sound emanating therefrom.
26. In combination, a resonator comprising opposed diaphragms of different resiliency each having an aperture therethrough and the apertures differing in size and a venturi for providing passage for sound between the diaphragms, and a diaphragm cooperating with the resonator and having an aperture therethrough smaller than either of the apertures of the first diaphragms.
27. In combination, a resonator comprising opposed diaphragms of different resiliency each having an aperture therethrough and the apertures differing in size and a venturi having transversely corrugated walls for providing passage for sound between the diaphragms, and a diaphragm cooperating with the resonator and having an aperture therethrough smaller than either of the apertures of the first diaphragms.
28. A resonator comprising a body portion having a venturi therethrough and a diaphragm at each end of the venturi.
29. A resonator comprising a body portion having a venturi therethrough provided with transversely corrugated walls and a diaphragm at each end of the venturi.
30. A resonator comprising a body portion having a venturi therethrough provided with transversely corrugated walls and a diaphragm at each end of the venturi, the diaphragms being of different resiliency and each provided with an aperture therethrough and the apertures differing in size.
31. In combination, a casing, a resonator in the casing and comprising opposed diaphragms and a venturi for providing passage for sound between the diaphragms, a carrier mounted in the casing and spaced a distance from said resonator and movable from position at a right angle to the axis of the casing to position at an inclination to said axis, and a diaphragm mounted in said carrier and movable therewith.
32. In combination, a casing, a resonator in the casing and comprising opposed diaphragms and a venturi for providing passage of sound between the diaphragms, a carrier mounted in the casing and spaced a distance from said resonator and movable from position at a right angle to the axis of the casing to position at an inclination to said axis and settable at intermediate positions of inclination to said axis, and a diaphragm mounted in said carrier and movable therewith.
33. A resonator comprising a body having a tapering opening provided with a stepped series of transverse corrugations extending from end to end of the opening.
34. A resonator for sound passage, said resonator comprising a body having a venturi opening of substantially hour-glass shape passing therethrough for passage of sound.
35. A resonator for sound passage, said resonator comprising a body having a venturi opening of substantially hour-glass shape passing therethrough and provided with a stepped series of transverse corrugations.
36. A resonator for a sound passage, said resonator comprising a light weight aluminum body of cylindrical exterior form and having a venturi opening of substantially hour-glass shape passing therethrough for passage of sound, said venturi opening being provided with a stepped series of transverse corrugations extending inwardly from each end of the venturi opening, the series meeting each other at about the middle transverse lines of the resonator; and a diaphragm across one end of the body.

Signed at New York in the county of New York and State of New York this 10th day of December A. D. 1924.

JAMES G. NOLEN.
